UNITED STATES PATENT OFFICE.

PHILLIP WHEELER, OF BRANCHPORT, NEW YORK.

RAILROAD-RAIL TIE AND CHAIR.

SPECIFICATION forming part of Letters Patent No. 503,184, dated August 15, 1893.

Application filed June 23, 1892. Serial No. 437,751. (No model.)

To all whom it may concern:

Be it known that I, PHILLIP WHEELER, of Branchport, in the county of Yates, in the State of New York, have invented new and useful 5 Improvements in Railroad - Rail Ties and Chairs, of which the following, taken in connection with the accompanying drawings, is a full, clear, and exact description.

My invention relates to railroad rail ties and 10 chairs and means for securing the rail removably thereon.

My object is to produce a railroad rail tie and chair combined, by which I am enabled to seat the rail quickly, firmly and securely; 15 cheap, durable in construction and of great utility.

My invention consists in the several novel features of construction and operation hereinafter described and which are specifically 20 set forth in the claim hereto annexed.

It is constructed as follows, reference being had to the accompanying drawings, in which—

Figure 1, is a view of my combined tie and rail chair complete, showing a portion of the 25 rail therein. Fig. 2, is an enlarged view of one end of a rail tie and seat. Fig. 3, is an end view of the construction shown in Fig. 2. Fig. 4, is a view of the seat, complete, forming part of the rail chair, detached. Fig. 5, 30 is a view of the shims, detached.

A—, is a tie constructed preferably of metal, as shown and having a bottom —1— and up turned edges —2—.

35 3—, are side pieces adapted to be secured to the side of the tie, as shown and extending up above the edges thereof, and is provided with a recess —a— extending beyond the side, as shown at —b—, for the purpose herein-after set forth.

4—, are lips extending out into the mouth 40 of the recess —a— and having their lower edges —c— adapted to fit over the upper face of the flange —5— of the rail —B—.

6—7, constitute shims, —6— lying within the tie, having bolts —8— passing through it, 45 the side of the tie, and the side plate —3—, by which bolts the parts above named are secured rigidly together and to each other. The shim —7— has its lower face inclined so that it may be interposed between the shim —6— 50 and the bottom of the rail, and then driven until the lips —4— clutch and securely hold the rail by the flanges, as shown in the drawings. The small recess —b— allows the flange of the rail to extend into it, when the rail is 55 turned edgewise, for the purpose of getting it within the recess —a— in the side plate —3—. When the shim —7— is driven home and the rail tightly clamped a spike —8— may be placed in the upper end of the shim next to 60 the flange of the rail to prevent its working out and becoming loose.

What I claim as my invention, and desire to secure by Letters Patent, is—

The combination with a tie, and the side 65 plates —3— having recesses —a— and —b— therein, inwardly projecting lips upon the upper face, means for securing said plates to the tie, and the shim interposed between it and the bottom of the rail, as described. 70

In witness whereof I have hereunto set my hand this 10th day of June, 1892.

PHILLIP WHEELER.

In presence of—

C. W. SMITH,
HOWARD P. DENISON.
